UNITED STATES PATENT OFFICE.

ISAAC B. KLEINERT, OF NEW YORK, N. Y., ASSIGNOR TO THE I. B. KLEINERT RUBBER COMPANY, OF SAME PLACE.

DESIGN FOR A DRESS-SHIELD.

SPECIFICATION forming part of Design No. 21,120, dated October 20, 1891.

Application filed September 24, 1891. Serial No. 406,745. Term of patent 7 years.

To all whom it may concern:

Be it known that I, ISAAC B. KLEINERT, a citizen of the United States, residing at New York, in the county of New York and State of New York, have invented and produced a new and original Design for Dress-Shields, of which the following is a specification, reference being had therein to the accompanying drawing.

This design is intended for dress or armpit shields, and the essential features thereof are shown in the accompanying drawing, which represents a side view of the same.

Referring now to said drawing by letters and figures, A represents the body-piece, having its bottom edge 1 and back edge 2 substantially straight. The top edge 3 is curved with an upward sweep in front, so as to make the front part or "horn" extend up to a considerable distance above the rear horn. The front edge 4 is straight, or substantially so, for the major part of its length, but curves slightly inward near the top, as shown. The sleeve part B has both its top and bottom edges curved, forming a crescent, with one

horn rising considerably higher than the other. 25 The two parts are usually made of separate pieces of material, but joined at their top or concave edges; yet they may be made of one piece, if desired. I generally bind the edges, as shown; but this is not essential, and tapes 30 C may be provided, if preferred.

What I claim as new is—

The design for dress-shields, having the sleeve-piece B curved at top and bottom, with its front part rising above the rear part, and the body-piece A having its top curved, its rear and bottom edges substantially straight, and its front edge also substantially straight for the major part of its length, but turning in at top, substantially as shown and described. 35 40

In testimony whereof I affix my signature, in presence of two witnesses, this 23d day of September, 1891.

ISAAC B. KLEINERT.
